ENGINE DECELERATION AND GOVERNOR
CONTROL

Albert G. H. Vanderpoel and Karl W. S. Ostling,
Los Angeles, Calif., assignors to California Ma-
chinery & Supply Co. Ltd., Los Angeles, Calif.,
a corporation of Delaware

Application February 21, 1938, Serial No. 191,684

20 Claims. (Cl. 123—103)

This invention has to do with apparatus for controlling internal combustion engines under various conditions of operation, particularly during idling and momentum operation at closed 5 throttle positions, and during governed speed operation at open throttle. The present apparatus has in common with other systems, such as those disclosed in Vanderpoel Patent No. 2,107,314, issued February 8, 1938, on Means for 10 automatically controlling flow of fuel mixtures to internal combustion engines, and in Ostling co-pending application Ser. No. 190,624, filed Feb. 15, 1938, on Engine control, a combination of controls, one operating to completely close the engine 15 or carburetor suction passage during deceleration or engine operation under momentum, and the other operating to maintain a predetermined or governed speed of engine operation in accordance with pressure conditions in the suction passage.

The patent and application referred to show the deceleration and governor controls applied to an auxiliary valve positioned in the suction passage at the outlet side of the throttle, the 20 throttle being manually operated in the usual manner and the auxiliary valve being automatically actuated independently of the throttle to control the engine during deceleration and high speed operation. One of the major objects 25 of the present invention is to apply deceleration and governor controls to the throttle itself, instead of to a separate or independent valve, so as to render the throttle automatically responsive to such controls and yet remain manually operable. In accordance with the invention, we connect 30 with the throttle a suitable governor, preferably of the suction operated type, and also a deceleration control that is capable of operation independently of the governor. In addition, we apply a manual operating connection to the 35 throttle in a manner such as to permit manual control thereof without, however, interfering with the governor and deceleration controls.

While, broadly contemplated, we may use any 40 suitable throttle operating deceleration control acting to cut-off the delivery of fuel to the engine, as by causing the throttle to completely close the suction passage, we preferably employ a type of control shown in Winfield Patent No. 2,101,605 45 issued December 7, 1937 on Automatic throttle control. This type of control is preferred because of its multiple functions of preventing engine stalling, cutting off the fuel (idling) supply to the engine, and operating the throttle to completely close the suction passage. As indicated

above, this control, together with the governor both are applied to the throttle and each within its operating range, controls the throttle independently of the other and independently of the manual throttle control. 5

The control system also preferably includes means for automatically admitting scavenging gas (air) to the engine manifold during momentum operation at closed throttle. While broadly, any suitable means may be used for admitting 10 the scavenging gas, we preferably use an independently operating air valve that is automatically responsive to abnormally low suction passage pressure to admit air to the manifold. 15

The invention has various objects and aspects 20 in addition to the features mentioned in the foregoing but all these will be more fully understood and explained to better advantage from the following detailed description of the invention in certain typical and illustrative forms. In the 25 description reference is had to the accompanying drawings, in which:

Fig. 1 is a side elevation of the carburetor and 30 suction passage, showing the fuel cut-off throttle control in section as indicated by line 1—1 of Fig. 2;

Fig. 2 is a section taken vertically through the suction passage;

Fig. 3 is a fragmentary elevation as viewed from 35 line 3—3 of Fig. 2;

Fig. 4 is a transverse section on line 4—4 of Fig. 2, showing the parts in closed throttle position;

Fig. 5 is a section on line 5—5 of Fig. 4; and

Fig. 6 is a sectional view showing the governor 40 parts as open throttle position.

It is to be understood that the invention is generally applicable to various types of engine fuel feeding apparatus utilizing a throttle controlled suction passage through which air is taken to the engine. For purposes of description, we have shown the control mechanisms that constitute the invention, to be associated with a down draft type carburetor 10, which may be taken as 45 illustrative of any suitable carburetor for supplying fuel to the suction passage. In the sectional view of Fig. 2, the carburetor is shown to comprise a suction passage 11 having an air inlet 12 and a fuel and air mixture outlet 13 connected 50 to the engine intake manifold 14. The flow of air to the engine is controlled by a throttle 15, typically the usual butterfly valve, carried on shaft 16 that is operated by a lever arm 17, see Fig. 3, to close the throttle. Arm 17 is rotatably 55

mounted on the throttle shaft 16, and the throttle is closed by engagement of an adjustable screw 18 carried by lug 19 integral with arm 17, with lug 20 on a collar 20a fixed to the throttle shaft. Arm 17 is rotated on shaft 16 against the resistance of the throttle closing spring 21a by manual operation of the usual throttle arm connection 21, to permit the throttle to open as hereinafter described. Choke valve 22 positioned 10 within the inlet 12 is mounted on a shaft 23 offset from the axial center of the carburetor suction passage and operated in the usual manner by lever 24 attached to its outer end.

It will be understood without the necessity for 15 specific illustration and detailed description, the carburetor 10 may contain any suitable means for delivering fuel to the suction passage 11 during normal or high speed engine operation at open throttle positions. During engine idling operation, fuel is supplied to the suction passage by way of idling by-pass passage 25, see Fig. 1, discharging through an orifice 26 whose effective size is regulated by needle valve 27. The usual orifices 25a are provided for bleeding air into the 20 idling passage past the throttle in its closed position. In its normal idling position, the throttle 15 is in substantially the solid line position I in which orifice 26 is openly exposed to the suction at the outlet side of the throttle. When fully 25 closed however, the throttle assumes the dotted line position C in which the throttle edge moves past or opposite orifice 26 to the point of closing it from the suction passage outlet 13, and thereby cuts off fuel delivery through the idling by-pass.

In Fig. 1, the deceleration and fuel cut-off throttle control generally indicated at A, is shown to comprise a body 28 suitably mounted on the carburetor body and containing a cylindric chamber 29 closed at its outer end by cover 30 carrying a stop screw 31. Chamber 29 contains a pressure responsive piston 32 having a rod 33 projecting through the inner closed end 34 of the body and attached by a pin and slot connection 35 with a lever arm 36 rotatably mounted on the throttle shaft 16. The piston chamber 29 is vented to the atmosphere at opposite sides of the piston 32 through orifices 37 and 38. The piston travel toward the right and in a throttle closing direction is yieldably resisted by a coil spring 39 confined between the piston and end wall 34 of the body. Under certain operating conditions, the spring resistance is overcome by depression communicated to chamber 29 at the right of the piston, causing the latter to travel to the point of engagement with sleeve 40. Then, as the depression in the chamber is further increased, additional piston travel in throttle closing direction is permitted by compression of spring 41 confined 45 between wall 34 of the flanged end 40a of sleeve 40. Spring 41 normally is maintained in partially compressed condition by adjustment of nut 42 so that the spring maintains a predetermined and greater resistance to the piston travel, than the 50 resistance imposed by spring 39.

When the depression in chamber 29 is relieved, 55 spring 39 moves piston 32 to a limiting position of engagement with stop screw 31, rotating the throttle an angular distance of around 5° from closed position to the dotted line position O. A lug 44 integral with arm 36, carries an adjustable stop screw 45 that engages a projection 46 fixed to the throttle shaft, to limit throttle movement in a closing direction and to open the throttle as 60 piston 32 moves toward the left. When the throt-

tle is rotated to full open position, projection 46 swings in the direction of the arrow away from stop 45 into engagement with a suitable stop 47 on the carburetor body.

The suction passage pressure at the outlet side 5 of the throttle is communicated to chamber 29 by way of passage 48 leading at 49, see Fig. 2, from a suitable location beyond the throttle and connecting at 50 with a bore 51 communicable with the piston chamber through passages 52 and 53. The bore 51 contains a valve 54 normally held in the raised position of Fig. 1 by a coil spring 55, and adapted to be moved downward to close one or both of passages 52 and 53 when engaged by the cam arm 56 carried on the end of the choke 10 valve shaft 28.

In the operation of the described throttle control, assume first that the engine is idling with the throttle in its idling position I. The suction passage pressure communicated from the outlet 20 side of the throttle to piston chamber 29 through passage 48, bore 51 and passages 52 and 53, causes the piston 32 to assume the position shown in Fig. 1, in which spring 39 is compressed and the piston is at substantially the point of engagement with the end of sleeve 40. If now for any 25 reason the engine tends to stall or miss fire, the resultant increase in the suction passage outlet pressure communicated to the piston chamber 29, causes spring 39 to move the piston toward the left and to open the throttle momentarily, or until manifold pressure is restored to normal, thus admitting more fuel and overcoming the stalling tendency. After the engine again is running smoothly and the normal depression is restored 30 in the suction passage outlet, piston 32 again moves to the right, returning the throttle to its normal idling position. It will be understood that in its throttle opening movement, the piston 32 overcomes the resistance of the throttle closing 35 spring 21a. When the throttle is opened beyond 40 idling position to increase the engine speed, the suction passage outlet pressure increases, causing spring 39 to move the piston into engagement with the stop screw 31.

The control device A not only operates to prevent stalling of the engine by momentarily opening the throttle beyond its idling position, but also to entirely or substantially entirely cut off the supply of fuel to the engine at times when the throttle is closed to idling position and the engine is operating under momentum, as when the engine is being driven by the vehicle. Assuming the throttle to be in its idling position I and the engine to be operating under momentum, an abnormally low pressure, below the normal idling pressure, is created within the suction passage outlet 13. The reduced pressure communicated to chamber 29, moves the piston toward the right against the resistance of both springs 39 and 41, and swings stop 45 a distance sufficient to permit the throttle 15 to close fully to the dotted line position C. In this position the throttle edge completely closes orifice 26 at the suction passage outlet side of the orifice and thereby cuts off the normal idling fuel delivery through passage 25, thus effecting a saving of fuel that otherwise would be wasted under such conditions, and preventing the formation of noxious gases as a result of incomplete fuel combustion within the 55 engine.

When the engine is being started and the choke valve 22 is closed, it may be desirable in effect to render the throttle control device A inoperative to insure that the throttle will remain in a proper closed (idling) position. As the choke valve is 60 65 70 75

closed, valve 54 is moved downwardly by arm 56 to a position in which valve 54 covers both ports 52a and 53a, to render the piston unresponsive to pressure conditions beyond the throttle. Advantage of the throttle control device may however be taken during starting when the choke valve is used, to cause the throttle to be automatically opened in the manner previously described and thereby prevent the engine from stalling should the fuel mixture become too rich. Under this condition, the choke may be closed to the extent of causing valve 54 to close only port 52a, leaving port 53a open to maintain communication of section from passage 48 to the piston chamber through passage 53. With the engine then idling, piston 32 will have been moved to the right just to the edge of passage 53, leaving the latter uncovered. Should the suction passage outlet pressure decrease due to the tendency of the engine to stall, piston 32 is permitted to move toward the left, away from passage 53, during which interval of travel the throttle will have been opened sufficiently to keep the engine running.

It will be understood that the described control device has its range of operation at closed or near closed throttle positions, to open the throttle beyond idling position to prevent stalling, or to cause the throttle to completely close the suction passage and cut off the supply of fuel to the engine.

Figs. 4 to 6 more particularly illustrate the governor control which, in the specific form illustrated, operates to maintain a predetermined maximum engine speed in accordance with the suction passage pressure beyond the throttle. The governor, generally indicated at 58, is contained within the cylinder end 59a of a body 59 mounted on the side of the suction passage opposite the control device A. The throttle shaft 16, journaled in suitable anti-friction bearings 60, extends outwardly from the suction passage through a chamber 61 within body 59, the chamber being suitably vented, as at 62, to maintain atmospheric pressure therein. The governor 58 comprises a pressure responsive member, preferably a piston 63, having a suitable lost motion connection with the throttle shaft arm 64. The connection may comprise a rod 65 having within bushing 67 a head 66 that is engageable with the seat end 68 of the bushing, as when the piston rotates the throttle in a closing direction, and is movable away from the seat to permit further closing of the throttle.

Operation of the governor piston is controlled by communication of suction passage pressure at the outlet side of the throttle, through port 69, passage 70 and opening 72 to the piston chamber 71. The communication between the piston chamber and suction passage is adjustable by a valve 73 positioned axially of the passage 69. Movement of the governor piston toward the left in response to increased suction communicated to chamber 71, is yieldably resisted by a coil spring 74, the expansive range of which is sufficient to move the throttle to full open position as later described. Movement of the piston in a valve closing direction is limited by engagement with a stop pin 75 slidable longitudinally within adjustment screw 76. The piston travel is yieldably arrested by a coil spring 77, having substantially greater resistance to compression than spring 74, attached to the stop pin head 75a and to the inner end 76a of the adjustment screw.

The limit of the governor piston travel toward

the left, and therefore the closed position of the throttle while under governor control, are determined by the position of the stop pin 75, and this position is variable by adjustment of screw 76, to maintain predetermined variable throttle positions and maximum governed engine speeds.

During engine operation under momentum at closed throttle, scavenging air is admitted to the suction passage and manifold beyond the throttle, under control of a valve, generally indicated at 78, contained within end portion 59b of the body 59 opposite the governor 58. The valve assembly 78 comprises a flanged air inlet tube 79 communicable through chamber 80, passage 81 extending below the throttle shaft, and passage 82, with the suction passage outlet beyond the throttle. Normally, communication between the inlet 79 and chamber 80, is closed by a valve 83 pressed by a coil spring 84 against seat 85 clamped between body portion 59b and the inlet tube flange 79a. The tubular valve stem 86 is movable longitudinally within a guide 87 integral with the tube 79. Opening of the valve 83 also is resisted by a coil spring 88 bearing against the inner end of screw 89 threaded through the valve stem 86. By adjustment of screw 89, and therefore the degree of compression of spring 88, the responsiveness of valve 83 to open at predetermined depression within chamber 80, may be accurately regulated.

In the foregoing description we have described individually the operations of the automatic fuel cut-off control A, the governor 58 and the air valve 78, so that now a more general explanation of the control apparatus as a whole, will serve to show the operating relationships between the parts thereof. We have explained how, during operation, the device A automatically opens the throttle to supply more fuel to the engine when the latter tends to stall, and how it operates to fully close the throttle, cutting off the idling fuel, during engine operation under momentum. During the last mentioned condition, the abnormally low pressure, or high depression, existing in the suction passage outlet, is communicated by way of passages 82 and 81 to the valve chamber 80, the combined compression resistances of springs 84 and 88 is predetermined to permit the valve 83 to open to the point of engagement of nut 90 with the guide 87, admitting air through the inlet 79. The air thus taken into the engine manifold scavenges the manifold and engine of unburned or incompletely burned fuel, thus eliminating and preventing the formation of noxious gases during momentum operation at closed throttle. As soon as the throttle is again opened, valve 83 of course seats to cut-off the admission of scavenging air.

Assume now that the accelerator rod 21 is moved against the resistance of the closing spring 21a to swing arm 17 in a throttle opening direction as indicated by the arrow in Fig. 3. Rotation of arm 17 does not itself open the throttle, but causes stop 18 to be moved away from the throttle shaft lug 20 to permit the throttle to be opened. During engine operation at closed throttle positions, rod 65 connecting the governor with the throttle shaft arm 64 will have been retracted into the piston bushing 67 to the position shown in Figs. 4 and 5, thus permitting the control device A to operate independently of the governor. As soon however as arm 17 is rotated to permit the throttle to open, the actual throttle opening force is supplied by the governor spring 74, and a comparatively weak spring 92 placed between the rod head 66 and the piston wall 93.

As previously mentioned, the expansive range of spring 74 is sufficient to advance piston 63 to full open throttle position, and spring 92 operates to take up the lost motion between rod 65 and the piston, by thrusting head 66 into engagement with the bushing seat 68 and to correspondingly rotate the throttle in an opening direction independently of the piston movement. Thus assuming arm 17 to be swung to open throttle position, the governor parts will assume the position shown in Fig. 6, with both springs 74 and 92 expanded and the piston 63 advanced to full open position.

Assuming now the throttle to be wide open, and the engine speed to increase beyond the maximum which the governor is set to maintain, the resultant depression in the suction passage outlet 13 communicated to the piston chamber 71, retracts the piston and closes the throttle to a position determined by the point at which further movement of the piston is arrested by its engagement with the yieldable stop pin 15. Just as the control device A is capable of operation independently of the governor, the governor operates independently of the device A, since in open throttle positions, the shaft carried projection 46 will have become rotated beyond the stop 45 whose position, corresponding to throttle position O, will have become limited by engagement of piston 32 with the stop screw 31.

36 We claim:

1. In engine fuel feeding apparatus comprising a suction passage having an inlet and an outlet, and a throttle valve in said passage; means for manually operating said throttle valve, a governor controlled in accordance with engine speed to close said valve and thereby govern the engine speed, and control means responsive to low suction passage pressures at the outlet side of the throttle for closing the throttle beyond its closed position under governor control, both said governor and control means being operable independently of said throttle operating means.

2. In engine fuel feeding apparatus comprising a suction passage having an inlet and an outlet, and a throttle valve in said passage; means for manually operating said throttle valve, a governor controlled in accordance with engine speed to close said valve and thereby govern the engine speed, and control means responsive to low suction passage pressures at the outlet side of the throttle for closing the throttle beyond its closed position under governor control, both said governor and control means being operable independently of said throttle operating means, said control means being responsive to a predetermined reduction in the suction passage pressure to maintain the throttle in substantially idling position, and operating to move the throttle in an opening direction when said pressure increases beyond that reduced pressure.

3. In engine fuel feeding apparatus comprising a suction passage having an inlet and an outlet, and a throttle valve in said passage; means for manually operating said throttle valve, a governor controlled in accordance with engine speed to close said valve and thereby govern the engine speed, and control means responsive to low suction passage pressures at the outlet side of the throttle for closing the throttle beyond its closed position under governor control, both said governor and control means being operable independently of said throttle operating means, said control means being responsive to suction passage pressure when the engine is operating under

momentum to cause said throttle to substantially completely close the suction passage.

4. In engine fuel feeding apparatus comprising a suction passage having an inlet and an outlet, means for supplying idling fuel to the suction passage and a throttle valve in said passage; means for manually operating said throttle valve, a governor controlled in accordance with engine speed to close said valve and thereby govern the engine speed, and control means responsive to low suction passage pressures at the outlet side of the throttle for closing the throttle beyond its closed position under governor control, both said governor and control means being operable independently of said throttle operating means, the last mentioned means being responsive to suction passage pressure when the engine is operating under momentum to cut off the delivery of idling fuel to said passage.

5. In engine fuel feeding apparatus comprising a suction passage having an inlet and an outlet, and a throttle valve in said passage; means for manually operating said throttle valve, a governor controlled in accordance with engine speed to close said valve and thereby govern the engine speed, control means responsive to low suction passage pressures at the outlet side of the throttle for closing the throttle beyond its closed position under governor control, both said governor and control means being operable independently of said throttle operating means, and means for admitting scavenging gas to said suction passage at the outlet side of the throttle when the engine is operating under momentum.

6. In engine fuel feeding apparatus comprising a suction passage having an inlet and an outlet, and a throttle valve in said passage; means for manually operating said throttle valve, a governor controlled in accordance with engine speeds to close said valve and thereby govern the engine speed, control means operating independently of said governor and responsive to low suction passage pressures at the outlet side of the throttle for closing the throttle beyond its closed position under governor control, both said governor and control means being operable independently of said throttle operating means, and means operating independently of the last mentioned means and governor for admitting scavenging gas to said suction passage at the outlet side of the throttle when the engine is operating under momentum.

7. In engine fuel feeding apparatus comprising a suction passage having an inlet and an outlet, and a throttle valve in said passage; means for manually operating said throttle valve, a governor controlled in accordance with engine speed to close said valve and thereby govern the engine speed, said governor including a pressure responsive member, a lost motion connection between said member and the throttle, and yielding means resisting valve closing movement of said pressure responsive member, and control means responsive to low suction passage pressures at the outlet side of the throttle for closing the throttle beyond its closed position under governor control, both said governor and control means being operable independently of said throttle operating means.

8. In engine fuel feeding apparatus comprising a suction passage having an inlet and an outlet, and a throttle valve in said passage; means for manually operating said throttle valve, a governor controlled in accordance with engine speed to close said valve and thereby govern the engine

speed, means connecting said governor with the throttle valve at one side of said suction passage, and control means connected with the throttle valve at the opposite side of said suction passage 5 and responsive to low suction passage pressures at the outlet side of the throttle for closing the throttle beyond its closed position under governor control, both said governor and control means being operable independently of said throttle 0 operating means.

9. In engine fuel feeding apparatus comprising a suction passage having an inlet and an outlet, and a throttle valve in said passage; means for manually operating said throttle valve, a governor 5 controlled in accordance with engine speed to close said valve and thereby govern the engine speed, means included in said governor for moving the throttle from closed to open position independently of said throttle operating means, 0 and control means responsive to low suction passage pressures at the outlet side of the throttle for closing the throttle beyond its closed position under governor control, both said governor and control means being operable independently of said throttle operating means.

10. In engine fuel feeding apparatus comprising a suction passage having an inlet and an outlet, and a throttle valve in said passage; means for manually operating said throttle valve, said means 0 comprising a throttle shaft and an arm movable in one direction with said shaft to close the throttle and movable relative to the shaft in an opposite direction, a governor controlled in accordance with engine speed to close said valve 5 and thereby govern the engine speed, and control means responsive to low suction passage pressures at the outlet side of the throttle for closing the throttle beyond its closed position under governor control, both said governor and control 0 means being operable independently of said throttle operating means.

11. In engine fuel feeding apparatus comprising a suction passage having an inlet and an outlet, and a throttle valve in said passage; means for 5 manually operating said throttle valve, said means comprising an operating member movable with the throttle to close the throttle, a governor controlled in accordance with engine speed to close said valve and thereby govern the engine speed, and control means responsive to low suction passage pressures at the outlet side of the throttle for closing the throttle beyond its closed position under governor control, both said governor and control means being adapted to close 5 the throttle independently of said throttle operating member.

12. In engine fuel feeding apparatus comprising a suction passage having an inlet and an outlet, a throttle valve in said passage and a shaft carrying the valve; a governor comprising a pressure responsive member actuated in accordance with the suction passage pressure at the outlet side of the throttle when the throttle is open beyond idling position, to move the throttle in a closing direction and thereby govern the engine speed, control means responsive to abnormally low suction passage pressure at the outlet side of the throttle to fully close the throttle beyond its closed position under governor control, a member operable manually to close said throttle, and a lost motion connection between said member and the throttle shaft whereby the shaft is rotatable in a throttle closing direction independently of said member.

13. In engine fuel feeding apparatus comprising

ing a suction passage having an inlet and an outlet, a throttle valve in said passage and a shaft carrying the valve; a governor comprising a pressure responsive member actuated in accordance with the suction passage pressure at the outlet side of the throttle when the throttle is open beyond idling position, to move the throttle in a closing direction and thereby govern the engine speed, control means responsive to abnormally low suction passage pressure at the outlet 5 side of the throttle to fully close the throttle beyond its closed position under governor control, a member operable manually to close said throttle, a lost motion connection between said member and the throttle shaft whereby the shaft is 10 rotatable in a throttle closing direction independently of said member, and yielding means for opening the throttle independently of said member.

14. In engine fuel feeding apparatus comprising a suction passage having an inlet and outlet, a throttle valve in said passage and a shaft carrying the valve; a governor comprising a pressure responsive member actuated in accordance with the suction passage pressure at the outlet side of the throttle when the throttle is open beyond idling position, to move the throttle in a closing direction and thereby govern the engine speed, control means responsive to abnormally low suction passage pressure at the outlet 15 side of the throttle to fully close the throttle beyond its closed position under governor control, a member operable manually to close said throttle, a lost motion connection between said member and the throttle shaft whereby the shaft is 20 rotatable in a throttle closing direction independently of said member, and yielding means for opening the throttle independently of said member.

15. In engine fuel feeding apparatus comprising a suction passage having an inlet and an outlet, a throttle valve in said passage and a shaft carrying the valve; a governor comprising a pressure responsive member actuated in accordance with the suction passage pressure at the outlet side of the throttle when the throttle is open beyond idling position, to move the throttle in a closing direction and thereby govern the 25 engine speed, control means responsive to abnormally low suction passage pressure at the outlet side of the throttle to fully close the throttle beyond its closed position under governor control, a member operable manually to close said throttle, a lost motion connection between said member and the throttle shaft whereby the shaft is 30 rotatable in a throttle closing direction independently of said member, and yielding means for opening the throttle independently of said member.

16. In engine fuel feeding apparatus comprising a suction passage having an inlet and an outlet, a throttle valve in said passage and a shaft carrying the valve; a governor comprising a pressure responsive member actuated in accordance with the suction passage pressure at the outlet side of the throttle when the throttle is open beyond idling position, to move the throttle in a closing direction and thereby govern the engine speed, control means responsive to abnormally low suction passage pressure at the outlet 35 side of the throttle to fully close the throttle beyond its closed position under governor control, a member operable manually to close said throttle, a lost motion connection between said member and the throttle shaft whereby the shaft is 40 rotatable in a throttle closing direction independently of said member, and yielding means for opening the throttle independently of said member.

- side of the throttle to fully close the throttle beyond its closed position under governor control, a lost motion connection between said governor and the throttle shaft permitting said control device to close the throttle independently of the governor, a throttle actuating arm rotatably mounted on said shaft and rotatable with the shaft to close the throttle, said shaft being rotatable relative to said arm in a throttle opening direction when the arm is in an open throttle position, and yielding means in said lost motion connection between the governor and throttle shaft, constantly tending to open the throttle.
17. In engine fuel feeding apparatus comprising a suction passage having an inlet and an outlet, a throttle valve in said passage and a shaft carrying the valve; a governor comprising a pressure responsive member actuated in accordance with the suction passage pressure at the outlet side of the throttle when the throttle is open beyond idling position, to move the throttle in a closing direction and thereby govern the engine speed, control means responsive to abnormally low suction passage pressure at the outlet side of the throttle to fully close the throttle beyond its closed position under governor control, means for admitting scavenging air to said suction passage at the outlet side of the throttle when the throttle is closed.
18. In engine fuel feeding apparatus comprising a suction passage having an inlet and an outlet, means for supplying idling fuel to the suction passage, and a throttle valve in said passage; means for manually operating said throttle valve, a governor controlled in accordance with engine operation above idling speed to move said valve in a closing direction and thereby govern the normal engine speed, and control means
19. In engine fuel feeding apparatus comprising a suction passage having an inlet and an outlet, means for supplying fuel to the suction passage through an idling fuel orifice in the wall thereof, and a throttle valve in said passage; means for manually operating said throttle valve, a governor controlled in accordance with engine operation above idling speed to move said valve in a closing direction and thereby govern the normal engine speed, and control means responsive to pressures below idling pressure existing in the suction passage at the outlet side of the throttle for closing the throttle to the point at which the throttle edge substantially completely closes said idling fuel orifice.
20. In engine fuel feeding apparatus comprising a suction passage having an inlet and an outlet, means for supplying idling fuel to the suction passage, and a throttle valve in said passage; means for manually operating said throttle valve, a governor controlled in accordance with engine operation above idling speed to move said valve in a closing direction and thereby govern the normal engine speed, and control means responsive to pressures below idling pressure existing in the suction passage at the outlet side of the throttle and operating to cut off the delivery of fuel from the idling fuel supply means into the suction passage.

responsive to pressures below idling pressure existing in the suction passage at the outlet side of the throttle and operating by virtue of throttle position to cut-off the delivery of idling fuel to the engine when the engine is operating under momentum.

ALBERT G. H. VANDERPOEL.
KARL W. S. OSTLING.
